UNITED STATES PATENT OFFICE.

FRANK H. WEAVER, OF JAMAICA, NEW YORK.

THREAD-HOLDER.

1,116,180.

Specification of Letters Patent.

Patented Nov. 3, 1914.

Application filed August 28, 1912. Serial No. 717,422.

To all whom it may concern:

Be it known that I, FRANK H. WEAVER, a citizen of the United States, residing at Jamaica, in the county of Queens and State 5 of New York, have invented certain new and useful Improvements in Thread-Holders, of which the following is a specification.

My invention relates to improvements in a thread holder, particularly adapted for 10 holding skeins of embroidery silk or other threads.

The object of my invention is to provide a thread holder which will incase and protect the threads; a further object of my invention is to construct the holder so that 15 one or more threads may be withdrawn at a time, without the remaining threads becoming entangled, and a still further object of my invention is to provide a thread holder 20 which can be manufactured at a very small cost.

Referring to the drawings, in which like references refer to like parts; Figure 1 is a plan view of the blank, before it is folded to form the holder; Figs. 2, 3, 4, and 5, are 25 views similar to Fig. 1, showing the successive folds made in the blank in forming the completed thread holder; and Fig. 6, is a perspective view of the completed 30 thread holder.

The blank 1, shown in Fig. 1, from which my improved thread holder is formed, consists of the body portion 2, and the extension flap 3, for securing the parts of the 35 body portion together, when completed. The blank 1, is preferably made of paper, and said blank is folded upon the dotted lines 4—5—6—7 and 8, as shown in Fig. 1.

The skein of threads 10, is placed longitudinally upon the blank, with the ends of 40 the threads projecting the same distance beyond each end of the body portion. The blank is folded upon the dotted line 4, as shown in Fig. 2, thus incasing the skein of 45 threads. The body portion is again folded along the line 5, as shown in Fig. 3. The folded body portion, as shown in Fig. 3, is

now folded upon itself along the transverse dotted line 8, into the position shown in Fig. 4. The flap 3, is now folded upon the 50 dotted lines 6 and 7 and wrapped around the folded body portion, as shown in Fig. 5. The flap 3 is equal in length to the body portion of the holder after the blank has been folded upon the transverse line 8, and when 55 the said flap is wrapped around the body portion said flap will add strength and rigidity to the holder and prevent the holder from bending when the threads are being withdrawn. The flap is sealed by wetting 60 the gummed portion 12, upon the flap, which is pressed firmly against the body portion of the holder. Thus the completed thread holder, as shown in Fig. 6, is formed. The loose ends of the threads are thus brought 65 together at one end of the completed holder. The folded portions of the threads, extending within the body portion of the holder, are separated by the folds made in the blank, as shown in Fig. 3, so that the threads will 70 not become entangled as they are withdrawn. The fold made in the body portion upon the transverse line 8, forms a bridge over which the threads will freely draw when the ends of the threads are pulled to 75 withdraw them from the holder.

Having thus described my invention I claim and desire to secure by Letters Patent:

A thread holder consisting of a body portion having three folded longitudinal sections of equal length and a plurality of folded half sections adapted to be wrapped around the body portion and entirely incase the body portion after it has been folded in the center of its length and thereby rigidly secure the folded sections of the body portion together. 80 85

In testimony whereof, I have affixed my signature in presence of two witnesses.

FRANK H. WEAVER.
